BABY'S BED GUARD

Milton N. Redman, Tompkins Corners, N. Y.

Application December 4, 1943, Serial No. 512,847

9 Claims. (Cl. 5—331)

This invention relates to a new and novel improvement in a child's sleeping accommodations. It is intended to provide a means whereby a daybed or the usual twin sized bed or ordinary cot could be converted into a crib or bed for the use of an infant.

It is particularly aimed to provide an auxiliary bed construction that could easily and effectively be applied to any ordinary sized bed which will be effective and durable in use, which will provide by its easy removal for the ready remaking of the bed after the bed is used, which shall be capable of storage in small space, which shall be readily transported so as to be useful on vacations or trips, and which may be manufactured at minimum cost and be of such construction so that it may be readily assembled or disassembled. A further object of this invention is to provide an auxiliary bed construction which will avoid the purchase of a child's size mattress or spring; and enable the use of the bed in its usual manner for adults by the simple and ready removal of the bed guard. It is a further aim of this invention to provide a structure that is capable of adjustment and adaptability to beds of various sizes.

The more specific objects and advantages will become apparent from the consideration of the description following, taken in connection with the accompanying drawings, illustrating an operative embodiment.

In said drawings:

Figure 1 is a view showing my improvement in perspective in connection with a daybed or twin bed;

Figure 2 is a horizontal section taken in the plane of the outer part of the transverse guard wall;

Figure 3 is a horizontal sectional view of one corner of the bed guard;

Figure 4 is a cross-sectional view taken on line 4—4 of Figure 5;

Fig. 4A is a cross-sectional view taken on line 4A—4A of Fig. 6;

Figure 5 is a fragmentary end elevation looking from the right end of the bed with a post annexed to it and with the bed guard side 42 removed;

Figure 6 is a fragmentary end elevation looking from the right of Figure 1 showing only the two posts with the leg 6 of the bed behind the post 7;

Figure 7 is a detailed perspective view showing a modification;

Figure 8 is a detailed vertical section taken through one of the legs of the bed guard;

Figure 9 is a perspective view similar to Figure 1 but showing the use of four sides instead of two;

Figure 10 is a horizontal cross-sectional view through one corner of the bed guard shown in Figure 9;

Figure 11 is a perspective view of a further modification;

Figure 12 is a perspective view of a final modification.

Referring specifically to the drawings wherein like reference characters designate like or similar parts, a bed is shown in Figure 1 having four legs, 2 and 6.

The bed 1 is to be taken as conventional and representative of a daybed or of one of a pair of twin beds or of a small size bed and in itself constitutes no part of any invention but to explain its use and coaction with my invention.

In carrying out my invention, I arrange the bed 1 in one corner of a room wherein one side edge of the bed and one end wall of the bed as shown in Figure 1 approximately touch the adjacent side wall and end wall of the room, so that a guard is required for only the other two sides which are not in the corner of the said room.

My invention consists essentially of a side wall 2 section generally designated 42 and a cross bed or end wall section generally designated 43, the same being collapsible or foldably connected together with hinges 10 and when unfolded and positioned as shown in Figure 1, coacting to form guards for the bed 1 and thus provide in combination with the bed 1, a crib or sleeping structure for a child or infant.

The side wall or guard 42 may consist of end posts 4 and 23 joined by connecting strips 17 and 18. Post 23 is connected by hinges 10 to strip 22B. The latter in turn is fixed to strips 22 and 22A, which in turn are connected by bolts to sections 29, 29A and which in turn are connected to post 14. Drop section 19A is connected to board 17 by hinges 16 and strips 19—19A have the spaces between them divided by rods 15, or the like at suitable distances. Strips 22—22A are likewise divided by rods 15, or the like, at suitable distances.

In order that the side wall 42 may be foldable in relation to the end or cross bed wall 43, the two are connected by hinges 10 as is also further indicated in Figure 2.

In order to detachably connect the post 4 against displacement to one of the bed legs 6, I provide a detachable auxiliary post 7 of a length to extend materially above the bed 1, as shown in Figs. 1 and 5, and fasten it in contact with one of the legs 6.

This auxiliary post 7 may have pairs of resilient

clasping fingers 26, or straps with buckles, or the like, whereby it may clasp or detachably connect one of the legs 6. The upper end of the auxiliary post 7 is provided with a pintle or the like 24. The guard or side section 42 is placed against the side of the bed as shown in Figures 1 and 6 and one post 4 has a hinged loop 27 or equivalent thereon which is slideably applicable for the pintle 24 to thus connect the guard 42 to the bed 1. Such guard section 42 is adjustable as to height since it has elements 5A, functioning as pedestals, adjustably connected to the lower end of the post 23 and post 4 by a screw-threaded shank 5A engaging correspondingly threaded sockets 6A.

Reverting to the end or cross bed section 43, it has end posts 14 and 23 joined by strips 22 and 22-A, with rods 15 secured thereto and disposed between them at any suitable distance with strips 22 and 22-A held firmly together by end piece 22-B. Post 23 is preferably hinged as at 10 to vertical strip 22B of the cross bed piece 43, so that when the parts are disassembled, they may be folded flat upon each other. Also, the post 14 while it need not extend to the floor, and it is intended not to extend to the floor, but only so far as to grip the far side of the bed, does extend below the opposing surface of the bed 1 to thereby prevent swinging of the cross bed or end section relative to the other guard on the hinges 10.

In order that the end or cross bed section 43 be adjustable as to width to accommodate beds 1 of different sizes, suitable means to attain this end may be used as shown in Figures 1, 2, 9 and 10. The strips 22-22A may be in sections connected to sections 29-29A by means of suitable bolts 11 which pass through slots 12 in the sections of the strips, which slots, by means of the adjacent strips, may be elongated as shown in Figure 2, to facilitate the adjustment mentioned.

Another suitable means to obtain adjustment and at the same time strengthen the strips is by using a pair of parallel metal sections fixed to post 14 as set forth in Figure 7. The curved edges 28 of the sections 29c would then fit around the strips 22 and 22-A to hold them firmly, it being intended that the bolts 11 pass through both the strips 22 and 22-A and the metal strips through the slot 30 of each section 29c.

I further provide a drop side 19c although this side may be rigidly connected as preferred. As shown, the drop side consists of strips 19 and 19-A held together by side strips 19-B. Strip 19-A is hinged at 16 to the strip 17 and which drop side is attached to be held against displacement by means of pins or the like 9 which is removable, pass through an opening in posts 23 and 4 into the strips 19, as shown in Figures 1 and 9. Also shown in Figures 2, 3, 4, 9 and 10.

In cases where a bed is used with but two sides as in Figure 1 and the bed has a high head-piece, I may attach a pintle thereto as shown in Figure 11. Such head-piece is designated 34 and the pintle 32, the same being of wood or metal and attached by screws to the head-piece 34. The hinged loop 33 on post 4 as in Figure 12, will function identically like the hinged loop 27 in Figure 6 and the auxiliary corner post 7 in Figure 6 is dispensed with.

Various changes may be resorted to within the spirit and scope of the invention. For instance, as shown in Figure 9, I may employ guards at 4 sides of the child's sleeping area instead of two as in Figure 1. In so doing, I use along the wall 75

side of the bed 1 and one end thereof a guard unit 40 which correspond to that used as the side wall sections 42 in Figure 1, and accordingly the same reference characters have been applied to the parts thereof. Additionally, I use an end guard unit generally designated 41 as an end or cross bed section which corresponds to that used as the cross bed section 43 and accordingly the same reference characters are applied to the parts thereof. When four sides are used the leg 14A is cut off flush with top of the bed 1 and the guard is held in position as in Figure 9 by the adjustment against displacement of the width of the cross-pieces by bolts 11. Legs 14 and 14A are fixed together by wagon bolts 15 provided with wing nuts 51, as shown in Figs. 9 and 10.

As various possible improvements might be made to the above invention and as various changes may be made in the improvement above set forth, it is to be understood that all matter herein set forth or shown in the accompanying drawings is to be interpreted as illustrative and not in a limiting sense.

Having thus described my invention, I claim 25 as new and desire to secure by Letters Patent:

1. An auxiliary bed construction to be applied to a bed to limit reposing space thereon for an infant and to guard against the infant's falling from the bed, and comprising a guard wall adapted to extend along one side of the bed, and having legs to rest on the floor, and a second extensible guard wall pivoted at one end to one end of the first guard wall and adapted to extend transversely across the bed to rest thereon, and means on the second guard wall extending downwardly therefrom adapted to engage an opposite side of the bed.

2. An auxiliary bed construction to be applied to a bed to limit reposing space thereon for an infant and to guard against the infant's falling from the bed, and comprising a guard wall adapted to extend along one side of the bed, and having legs to rest on the floor, and a second extensible guard wall pivoted at one end to one end of the first guard wall and adapted to extend transversely across the bed to rest thereon, means on the second guard wall extending downwardly therefrom adapted to engage an opposite side of the bed, and means on the first guard wall to adjust the height thereof.

3. An auxiliary bed construction to be applied to a bed to limit reposing space thereon for an infant and to guard against the infant's falling from the bed, and comprising a guard wall adapted to extend along one side of the bed, and having legs to rest on the floor, a second extensible guard wall hinged at one end to one end of the first guard wall and adapted to extend across the bed and rest thereon, means at the opposite end of said second guard wall extending downwardly therefrom, adapted to engage an opposite side of the bed, said first guard wall having a section hinged at its lower edge to said guard wall, and means to retain said section in the plane of said first guard wall.

4. An auxiliary bed construction to be applied to a bed to limit reposing space thereon for an infant and to guard against the infant's falling from the bed, and comprising a guard wall adapted to extend along one side of the bed, and having legs to rest on the floor, and a second extensible guard wall pivoted at one end to one end of the first guard wall and adapted to extend across the bed to rest thereon, means on the second guard wall extending downwardly therefrom

adapted to engage an opposite side of the bed, and means to attach a leg of the first guard wall to a leg of the bed.

5. An auxiliary bed construction to be applied to a bed to limit reposing space thereon for an infant and to guard against the infant's falling from the bed, and comprising a guard wall adapted to extend along one side of the bed, and having legs to rest on the floor, and a second extensible guard wall pivoted at one end to one end of the first guard wall and adapted to extend across the bed to rest thereon, means on the second guard wall extending downwardly therefrom adapted to engage an opposite side of the bed, a post adapted to be attached to a leg of the bed, and means to attach said post to the first guard wall.

6. An auxiliary bed construction to be applied to a bed to limit reposing space thereon for an infant and to guard against the infant's falling from the bed, and comprising a guard wall adapted to extend along one side of the bed, and having legs to rest on the floor, and a second extensible guard wall pivoted at one end to one end of the first guard wall and adapted to extend across the bed to rest thereon, means on the second guard wall extending downwardly therefrom adapted to engage an opposite side of the bed, a post adapted to be attached to a leg of the bed, means to attach said post to the first guard wall, and means to adjust the height of the first guard wall.

7. An auxiliary bed construction to be applied to a bed to limit reposing space thereon for an infant and to guard against the infant's falling from the bed, and comprising a guard wall adapted to extend along one wall of the bed, and

having legs to rest on the floor, and a second extensible guard wall pivoted at one end of one end of the first guard wall, and adapted to extend entirely across the bed, said second guard wall having at the opposite end thereof, a downwardly extending member terminating short of the floor, and adapted to engage an opposite side of the bed to prevent swinging movement of the second guard wall relative to the first guard wall.

10. An auxiliary bed construction comprising a pair of parallel side guard walls adapted to run along opposite sides of a bed and having legs to rest on the floor, and a pair of parallel end guard walls adapted to be disposed transversely of the bed, and above the same, one end wall being hinged at one end to one end of one side wall, and the other end wall being hinged at one end to one end of the opposite side wall, means to attach the other ends of said end walls to the other 20 ends of said side walls, said end walls being adjustable in length.

15. An auxiliary bed construction comprising a pair of parallel side guard walls adapted to run along opposite sides of a bed and having legs to rest on the floor, and a pair of parallel end guard walls adapted to be disposed transversely of the bed, and above the same, one end wall being hinged at one end to one end of one side wall, and the other end wall being hinged at one end to one end of the opposite side wall, means to attach the other ends of said end walls to the other 25 ends of said side walls, said end walls being adjustable in length, said side walls each having a section swingable downwardly about its lower edge, and means to maintain said sections in the 30 planes of their respective side walls.

MILTON N. REDMAN.
